US0D1096933S

(12) **United States Design Patent** (10) **Patent No.:** **US D1,096,933 S**
(45) **Date of Patent:** **** Oct. 7, 2025**

(54) **MULTIFUNCTION PRINTER**

(71) **Applicant:** **Zhuhai Pantum Electronics Co., Ltd.**,
Guangdong (CN)

(72) **Inventors:** **Aiguo Yin**, Zhuhai (CN); **Xining Ding**,
Zhuhai (CN); **Xinchao He**, Zhuhai
(CN); **Juzheng Xia**, Zhuhai (CN); **Hua
Tang**, Zhuhai (CN)

(73) **Assignee:** **Zhuhai Pantum Electronics Co., Ltd.**,
Zhuhai (CN)

(**) **Term:** **15 Years**

(21) **Appl. No.:** **29/939,381**

(22) **Filed:** **Apr. 26, 2024**

Related U.S. Application Data

(62) Division of application No. 35/518,064, filed on Apr.
25, 2023 (U.S. filing date under 35 U.S.C. 384), and
having an international filing date of Apr. 25, 2023,
now Pat. No. Des. 1,052,646.

(57) **CLAIM**

The ornamental design for a multifunction printer as shown
and described.

DESCRIPTION

FIG. 1 is a front view of a multifunction printer of our new
design;

FIG. 2 is a rear view thereof;

FIG. 3 is a left view thereof;

FIG. 4 is a right view thereof;

FIG. 5 is a top view thereof; and,

FIG. 6 is a perspective view thereof.

The broken lines immediately adjacent to the unshaded
claimed surfaces depict the bounds of the claimed design,
while all other broken lines are directed to environment. The
broken lines form no part of the claimed design.

1 Claim, 6 Drawing Sheets
